Des. 221,950

Patented Sept. 21, 1971

221,950

HOUSING FOR A VEHICLE IGNITION SYSTEM

Paul F. Eidingen, 2923 Florence St.,
Berkeley, Calif. 94705

Filed Mar. 19, 1970, Ser. No. 21,974

Term of patent 14 years

Int. Cl. D13—99

U.S. Cl. D26—5

Fig. 1

Fig. 2

Fig. 3

FIG. 1 is a front isometric view of the housing for a vehicle ignition system of the present invention;

FIG. 2 is a rear isometric view of the housing for a vehicle ignition system shown in FIG. 1;

FIG. 3 is a bottom view of the housing for a vehicle ignition system shown in FIGS. 1 and 2.

I claim:

The ornamental design for a housing for a vehicle ignition system, substantially as shown and described.
